UNITED STATES PATENT OFFICE.

ALFRED F. GOSHORN, OF CANTON, OHIO.

CURTAIN-HANGER.

SPECIFICATION forming part of Letters Patent No. 702,420, dated June 17, 1902.

Application filed July 30, 1901. Serial No. 70,224. (No model.)

To all whom it may concern:

Be it known that I, ALFRED F. GOSHORN, a citizen of the United States, residing at Canton, in the county of Stark and State of Ohio, 5 have invented a certain new and useful Curtain-Hanger, of which the following is a specification.

My invention relates to an improved hanger for supporting curtains and draping the same 10 on windows or elsewhere; and the objects of my improvements are to provide a hanger on which the curtain can be readily attached or detached and one on which the curtain can be draped on a straight or curved line and at 15 any desired distance from the window-frame by suitable variations in the lengths of the parts. I attain these objects by the mechanism illustrated in the accompanying drawings, in which—

20 Figure 1 is a perspective view of the hanger arranged for draping in a curved line; Fig. 2, a sectional view showing the hanger attached to a window-frame. Figs. 3 and 4 are similar views showing other forms of attachment. Fig. 5 is a detached perspective view of a double rod; Fig. 6, a similar view of a single rod; Fig. 7, a perspective view of the hanger arranged for draping in a straight line and showing notched plates; Fig. 8, a de- 25 tached perspective view of one of the two similar notched plates, and Fig. 9 is a cross-section showing attachment by two similar notched plates.

Similar numerals refer to similar parts 30 throughout the several views.

The hanger-plates 1 and 2 may be made of wood, metal, or other suitable material and are respectively provided with corresponding apertures or holes 3 for the passing of the 35 nails or screws 4 used for attaching the plate to the window-frame 5. The hanger-rods 6 may be made single or double of a thin bar or stiff wire and have their inner ends 7 bent down substantially at a right angle, with a 40 loop or eye 8 formed thereon, and their outer ends 9 drawn or ground to a sharp point, the same being curved by bending upward to form the pin-pointed hooks 10.

The rods 6 can be made of various lengths 45 and are so directed outward that the pointed hooks 10 on the outer ends thereof are spaced, preferably, similar distances apart and form

with each other a curved line, as illustrated in Fig. 1, or a straight line, as illustrated in Fig. 7.

For attaching the hanger to the window-frame 5 the bent-down rear ends 7 and the loops or eyes 8 thereon are placed between the respective plates 1 and 2, so said loops or eyes will register with the respective holes 3 in said plates. The nails or screws 4 are then passed through said holes and loops or eyes and driven into the window-frame 5, which completes the attachment, as illustrated in Fig. 2. The rods 6 pass over and 50 rest on the upper edge 11 of the plate 1, giving strength and steadiness to the hooks; or similar plates 1^a and 2^a, provided, respectively, with notches 8^a in their contiguous faces, adapted, respectively, to receive the 55 bent-down inner ends 7 of the rods and the loops or eyes 8 thereon, can be used, thus permitting the plates to close in contact, as illustrated in Fig. 7.

If it be desired, the plate 2 or 2^a can be 60 omitted and the turned-down inner ends of the rods fastened directly against the window-frame, as illustrated in Fig. 3, or both plates can be omitted and the head of the nail or screw engage the loops or eyes directly, 65 as illustrated in Fig. 4.

The hanger being attached to the window-frame, the curtain 12 is attached and draped on the outer ends of the rods 6, as illustrated in Fig. 2, by engagement of the sharpened 70 hooks therewith. These pin-pointed hooks can pass through the body of the curtain or may engage therewith in any other suitable manner. By means of the multiplicity of 75 points of engagement the curtain can be gathered in folds and draped in any manner to suit the fancy of the draper, and the rods are 80 preferably made long enough to hang the curtain away from the window, leaving a clear 85 space therebetween for the proper operation 90 of a window-shade. The curtain can also be readily removed from the hanger by merely 95 lifting it from the hooks.

Having described my invention, what I claim as new, and desire to secure by Letters 100 Patent, is—

1. For a curtain-hanger, the combination of a window-frame, a multiplicity of rods directed outward from said frame, there being

pin-pointed hooks formed on the outer free ends of said rods, and means for rigidly attaching the inner ends of the rods directly to the window-frame, substantially as specified.

- 5 2. For a curtain-hanger, the combination of a window-frame, a multiplicity of rods directed outward from said frame, there being means for attaching a curtain to the outer ends of said rods and bent-down loops formed on the inner ends thereof, a plate located on the outer side of said loops having its upper edge in contact with said rods, there being holes in said plate registering respectively with said loops, and screws passing respectively through said holes and loops into the window-frame, substantially as specified.
- 15 3. For a curtain-hanger, the combination of a window-frame, a multiplicity of rods di-

rected outward from said frame, there being means for attaching a curtain to the outer ends of said rods and bent-down loops formed on the inner ends thereof, plates located on the outer and inner sides of said loops, the upper edge of said outer plate being in contact with said rods, there being holes in said plates registering respectively with said loops, and screws passing respectively through said holes and loops into the window-frame, substantially as specified.

In testimony whereof I have signed my name to this specification in the presence of two subscribing witnesses.

ALFRED F. GOSHORN.
